MAY E. RHOADS, OF NEW YORK, N. Y.

WOMAN'S WORKING-GARMENT.

1,305,307.

Specification of Letters Patent. Patented June 3, 1919.

Application filed August 5, 1918. Serial No. 248,295.

To all whom it may concern:

Be it known that I, MAY E. RHOADS, a citizen of the United States, residing in the city, county, and State of New York, have 5 invented certain new and useful Improvements in Women's Working-Garments, of which the following is a specification.

My invention relates to women's garments and more particularly to garments which 10 shall be especially suitable for women engaged in manual industrial work as distinguished from clerical work or domestic service; the improved garments of my invention may, however, be used to advantage in these 15 last named vocations as well as in many other situations not strictly industrial.

It is the object of my invention to provide a simply designed, simply and inexpensively made, and durable garment for women 20 working on the farm or in the machine shop, running elevators, driving motor cars, serving as conductors or motormen, or, in short, laboring in any one of the manifold capacities opened to women by modern social and 25 industrial conditions. The majority of these occupations have, until quite recently, been almost exclusively confined to men.

In practising callings of the general class specified the inappropriateness of conventional woman's attire is obvious and has 30 long been recognized. Flowing skirts, loose sleeves and the like, not only directly interfere with the workers' speed and efficiency, but are also likely to be caught by projecting 35 parts of fixtures or machinery, thus becoming a source of actual danger to the wearer. On the other hand women themselves have objected, from considerations of natural modesty, to donning male clothing, 40 and practical sociologists have seen the danger of permitting them to do so.

A suitable garment for women engaged in occupations of the class above referred to should have the following characteristics:

45 First: It should provide the utmost freedom of movement while at the same time, clinging sufficiently close to the person, so that parts of the garment may not be caught by fixtures or doors or by machinery, driving 50 belting and the like.

Second: It should be modest and womanly in design and should render its wearer readily distinguishable from a man even at a considerable distance.

55 Third: It should cover the body quite

completely so as to keep its wearer as clean as possible.

Fourth: It should be capable of being quickly and easily put on or off and its fastenings should therefore be few and simple. 60

Fifth: Since the workers' employment is usually more or less public as well as on a time basis, the garment should be capable of being quickly opened and closed for the performance of the necessary natural health 65 functions with as little exposure of the person as possible and with a minimum consumption of time.

Sixth: It should be so designed that, upon the street, while traveling to and from her 70 place of employment, it will differentiate its wearer as little as possible from other women.

Seventh: It should comprise a minimum 75 number of pieces and be made of a minimum amount of material and should be so designed as to be readily, quickly and easily laundried.

The foregoing requirements, and others not specifically named, are all satisfied by 80 the improved garment of my invention.

Briefly and broadly described, the garment of my invention comprises three separate parts, viz., a pair of bloomers and a waist to be worn together as one when actually working; and an outer smock or combination skirt and demi-blouse or shoulder straps to be worn over and attached to the work clothes (bloomers and waist) for street 85 and similar use. 90

The invention resides in certain special features to which attention will be particularly drawn hereinafter.

My invention will be better understood by referring to the accompanying drawings in 95 which Figure 1 represents the garment as it appears when worn for street or like use, as, e. g., when the wearer is going to and from her work; Fig. 2 is a view showing the combined waist and bloomers as they appear 100 when the wearer is engaged in actual work; Fig. 3 is a plan view of the outer smock when removed from the remainder of the garment and flattened out, portions of the smock being folded back to better show details; Fig. 4 is a plan view, similar to Fig. 3, showing the waist; Fig. 5 is a side view showing the bloomers, in accurate detail; Fig. 6 is a view, similar to Fig. 5, but showing the bloomers open or let down behind 105 110

for the performance of necessary health functions; Fig. 7 is a view, taken from the inside, of the front abdominal portion of the bloomers; Fig. 8 is a view, very much enlarged, of the top of Fig. 7 with the fastening tapes folded inwardly; Fig. 9 is a section greatly enlarged along the line 9—9 of Fig. 5 showing the tapes used in drawing in the legs of the bloomers upon the legs of the wearer; and Fig. 10 is a view showing, on a somewhat enlarged scale, that portion of the bloomer leg which lies below the line 9—9 of Fig. 5 with the flaps thereof opened up and thrown back so as to show the fastening tape in natural position.

Referring to the drawings the work clothes proper comprise a waist, 1, and a pair of bloomers, 2. The waist is preferably, fairly high in the neck, and opens down the front along one side; snap fasteners, 3, are used to keep the waist closed but buttons or other usual fastening means may be substituted if preferred.

The sleeves should, preferably, be full length and embrace the wrists closely. Buttons, 4, may be used to maintain the desired closeness of fit.

A row of buttons, 5, is provided on the front of the waist; these buttons begin at the shoulder and extend from one-third to one-half the entire distance to the waist-line or approximately to points on a line with the arm-pits and are disposed symmetrically on each side of the center.

The bloomers, 2, are made to fit snugly at the waist line and below the knee but are otherwise made rather loose and roomy. They are split or divided on each side at, 6, from the waist-line down to a point about on a line with the crotch. These divided portions are held in closed position by snap fasteners, 7, and by hooks, 8, and eyes, 9, attached to the ends of the waist band, 10.

The bloomer legs are also split, from the bottom up, on the outside of each to a point above the knee, the divided portions being arranged to be held together by buttons, 11. The lower part of the leg, from a point just below the knee to the bottom, is fitted closely to the person, as previously stated.

The bottom portion of each bloomer leg is also provided with an elastic tape, 12, which runs around the leg the ends being respectively sewed fast on the two sides of the dividing line and other points of the tape being fastened at a point, 13, diametrically opposite the dividing line and also at points, 14, on the front and back of the leg.

Elastic tapes, 15, are respectively sewed fast to the inner side and near the ends of the front section of waist band, 10. The free ends of these tapes are respectively provided with a hook, 16, and eye, 17, by which they may be fastened together behind the back (Fig. 6). This enables the

rear section or seat of the bloomers to be opened away from the front section and let down for the performance of necessary natural health functions quite independently, of the front section which will remain in place thus completely avoiding any necessary exposure of the person.

The waist band of the bloomers should lie outside of and cover the waist band of the waist.

Pockets, 18, preferably of the "patch" type, are provided on each side of the bloomers and readily accessible through the split, 6.

The smock, 19, comprises two substantially identical, and preferably integral, front and back sections, 20, 21, arranged to button together along the lateral edges, 22; and of a bottom broader portion to constitute a skirt, 23; the buttons, 24, need only be at the waist line and, perhaps, at one other point, as shown, since the smock is worn over the bloomers and waist or work clothes so that no exposure of lingerie can take place.

Each smock section has a central portion, 25, and, 26, for the front and back respectively, which extend upwardly above the waist line, are shaped at the top, 27, to fit the neck, and are provided with shoulder straps adapted to be fastened together by snap fasteners, 28. These top portions are much narrower than the width of the torso and are, indeed, only wide enough to just extend beyond the buttons, 5, on the waist, 100. Button holes, 29, are provided on the lateral edges of the top portions and are adapted to be engaged with the buttons, 5, thus fastening the upper portion of the smock in place and preventing any twisting thereof.

From this it will be seen that the lateral portions of the waist, 1, of the work clothes combine with the central upper portions, 25, 26, of the smock, 19, to constitute the 110 waist for the skirt of the smock.

The smock, being made up of two flat sections, front and back, of simple outline and readily separable from one another, may be easily and quickly laundered.

With the smock in place over the waist and bloomers, as shown in Fig. 1, it is obvious that the wearer presents a neat and refined appearance and will attract no undue attention upon the street by reason of any peculiarities of dress. Reaching her place of work she can, in an instant, throw off the smock and be ready for work while the smock may be rolled up in small compass and laid to one side. When she has finished her day's work she can, just as readily and quickly, again be ready for the street. And it is obvious that no spacious and elaborate dressing rooms are needed for these changes; indeed no dressing rooms at all are 130

needed for this purpose as it is clear that no trace of immodesty is attached to the making of these changes in the open. Should the wearer not desire to remove the smock or outer garment but prefer to be outwardly conventionally attired, the advantages secured through the elimination of petticoats and the substitution of bloomers therefor are apparent, as previously pointed out. When thus attired, the necessary natural health functions may be readily and easily performed by disengaging the buttons 24 at one side of the outer garment and wholly or partially moving the portion 21 to one side permitting ready access to the back portion of the bloomers.

Changes and variations of detail may obviously be made in the garment as described and shown without departing from the spirit of the invention as defined in the following claims.

I claim—

1. In an improved garment for women, the combination of an inner garment and an outer garment, the latter having a skirt portion and portions extending from the top of the skirt in front and back and over the shoulders, said top portions being narrower than the inner garment and said front top

portion having its lateral edges adapted to be detachably connected to said inner garment at points approximately on a line with the arm-pits and supported from the shoulders of the wearer.

2. In an improved garment for women, the combination of an inner garment and an outer garment adapted to be detachably connected together at a point approximately on a line with the arm-pits, said outer garment comprising two substantially similar front and back sections the lower portions of which are adapted to be joined together at their lateral edges so as to constitute a skirt while the upper portions are narrower than the body of the wearer and adapted to be detachably connected together at at least one shoulder and supported from the shoulders of the wearer.

3. In an improved garment for women, the combination of an outer garment having a skirt portion comprising front and back members detachably connected at their side edges, and of an inner garment having a drop seat.

In testimony whereof I have signed my name this 3rd day of August, 1918.

MAY E. RHOADS.
